UNITED STATES PATENT OFFICE

ARCHIE H. BECHTOL, OF DAYTONA BEACH, FLORIDA, AND WALTER A. TRATSCH, OF CHICAGO, ILLINOIS

DESIGN FOR A PISTOL RANGE

Application filed August 11, 1930. Serial No. 36,629. Term of patent 14 years.

To all whom it may concern:

Be it known that we, ARCHIE H. BECHTOL and WALTER A. TRATSCH, both citizens of the United States, residing at Daytona Beach, Florida, and Chicago, Illinois, respectively, have invented a new, original, and ornamental Design for Pistol Range, of which the following is a specification, reference being had to the accompanying drawing, forming part thereof.

The figure is a perspective view of a pistol range showing our new design.

We claim:

The ornamental design for a pistol range as shown.

In testimony whereof we affix our signatures.

ARCHIE H. BECHTOL.
WALTER A. TRATSCH.
